UNITED STATES PATENT OFFICE.

JOHN E. LARKIN, OF POQUONOCK, AND JARVIS E. TOWER, OF RAINBOW,
CONNECTICUT.

ATTACHMENT FOR CALENDER-ROLLS FOR PAPER.

SPECIFICATION forming part of Letters Patent No. 268,809, dated December 12, 1882.

Application filed October 23, 1882. (No model.)

To all whom it may concern:

Be it known that we, JOHN E. LARKIN, of Poquonock, in the county of Hartford and State of Connecticut, and JARVIS E. TOWER, of Rainbow, in said county and State, have invented certain new and useful Improvements in an Attachment for Calender-Rolls for Paper, of which the following is a description, reference being had to the accompanying drawings, where—

Figure 1 is a front view of our device attached to a stack of three rolls. Fig. 2 is a side view of the same. Fig. 3 is a detail sectional view of the adjusting device, in which the buffer-roll is journaled. Fig. 4 is a detail view of cam-slot in buffer-roll journal.

Our invention relates to devices used for forming a smooth, even surface on the paper-rolls used in calenders; and it consists in a buffer-roll having a roughened or cutting surface, and so arranged upon the frame of the stack of rolls as to resurface the paper-roll without removing it from the stack.

In the accompanying drawings, the letter *a* denotes the frame of calender having a stack of three rolls and made in the usual manner, the rolls *b* and *d* being of iron and *c* of paper. Projecting stands *e* are cast integral with or secured to the frame *a*, and have inclined mortises *f* in their upper surface, the bottom of the mortise bearing the adjustable pillow-block *g* dovetailed to it, as shown in Fig. 4. The blocks *g* are reciprocated on their beds by screws *h*, pivotally connected to each, and are guided by pins *g'* entering suitable openings in the frame or stand. A lock-nut, *h'*, serves to hold rod *h*, which turns in a threaded hole in the stand in any desired part of its path. In these pillow-blocks are journaled the shaft *i*, which bears the buffer-roll *k*, having a suitable cutting-surface—as emery, or the like—adapted to cut and smooth the surface of the paper-roll *c*. Near one end the shaft *i* has a peripheral cam-slot, *i''*, into which takes the screw-pin *l*, by means of which the buffer-roll is given an endwise play or vibration as it revolves. A paper-reel, *m*, is fixed to the floor in a suitable position in front of the stack, and is turned by belts from a pulley on the stack-rolls. From

the pulley on this reel a belt connects with pulley *i'*, fast to shaft *i*.

When the calender is in ordinary use the buffer-roll is withdrawn from contact with the roll *c* by means of the devices described; but when the paper-roll is to be resurfaced the buffer-roll is placed in contact with it and held there, and by means of connecting-belts and pulleys rapidly revolved against it, thoroughly grinding and smoothing its surface as it revolves, the endwise play greatly aiding in the operation. As soon as a proper surface is regained the buffer-roll is retracted, and the usual work of the calender resumed with but little interruption.

Prior to our invention it has been the custom to remove these paper-rolls when their surface has become dented and imperfect, and regrind them or cut them true in a lathe at a loss of time and labor. Our device saves most of this, as the paper-rolls are recut in place in the stack. The inclined position of the pillow-blocks and their bed in relation to the fixed driving-pulley (in this instance on the reel) enables us to move the buffer-roll to and from the paper-roll without altering the tension of the belt.

We claim as our improvement—

1. In combination, in a calender, a paper-roll, *c*, and an adjustable vibrating buffer-roll having a grinding-surface, and actuating mechanism, all substantially as described.
2. In a calender, a laterally-adjustable buffer-roll and operating mechanism, whereby a paper-roll may be resurfaced in place in the stack, all substantially as described.
3. In a calender, a stand or bearing for a buffer-roll, having an inclined bed in which the pillow-block is dovetailed and reciprocated, all substantially as described.
4. In a calender, in combination, buffer-roll *k*, stands *e*, having mortised bed and a guide-socket, pillow-blocks *g*, having guides *g'*, and screw-rod *h*, all substantially as described.

JOHN E. LARKIN.
JARVIS E. TOWER.
